UNITED STATES PATENT OFFICE.

ALFRED E. McMILLAN, OF NEW YORK, N. Y.

STAMP-PLACING MACHINE.

Application filed July 14, 1923. Serial No. 651,579.

To all whom it may concern:

Be it known that I, ALFRED E. McMILLAN, a subject of Great Britain, residing at New York, in the county of New York and State of New York, have invented certain new and useful Improvements in Stamp-Placing Machines; and I do hereby declare the following to be a full, clear, and exact description of the invention, such as will enable others skilled in the art to which it appertains to make and use the same.

This invention relates to stamp placing machines and more particularly to the hand operated type which is placed upon an envelop where the stamp is to be affixed and the machine there operated for severing the stamp and applying it to the envelop.

The objects of this invention are to provide improved means for severing the stamp from the roll and applying it to the envelop or the like; to provide improved positive feed for the stamp; to moisten each stamp as it is being applied; to avoid use of felt or other wipers for moistening the stamp; to thus increase the sanitary condition of the device and also to insure proper moistening of the stamps at all times; to provide for supplying water for each stamp as it is affixed; to enable the user to observe the amount of water in the container; to obtain an even supply of water; to secure simplicity of construction and operation and to obtain other advantages and results as may be brought out in the following description.

Referring to the accompanying drawing in which like numerals of reference indicate similar parts throughout the several views,

Figures 1 and 2 are elevations looking at opposite sides of the device;

Figure 3 is an edge view looking in the direction indicated by arrow (3) of Fig. 1;

Figure 4 is an opposite edge view looking in the direction indicated by arrow (4) of Fig. 2;

Figure 5 is a sectional view on line 5—5 of Fig. 3 looking in the direction indicated by the arrows: and

Figure 6 is a similar sectional view showing the parts in depressed position.

In the specific embodiment of the invention illustrated in said drawings the reference numeral 1 indicates a housing which is

U-shape in cross-section and has projecting from the upper end a collar 2 upon which

is slidably mounted a handle 3. Handle 3 is secured by means of bolt 4 passing through the collar and the upper end of the housing, to a slidable member 5 which is arranged within said housing and engages the side walls thereof. The slidable member 5 is constructed to provide a stamp engaging face 6 at its lower end by means of which pressure may be exerted upon the stamp for causing the stamp to come in proper contact with the envelop or the like in order to become affixed thereto. The U-shaped housing 1 is provided with a bottom plate 7 having an opening 8 preferably the same size as the bottom 6 of the slidable member so that when the slidable member is depressed the bottom thereof substantially fills the opening 8 in the bottom plate of the housing. The slidable member carries a knife 9 which co-operates with a similar knife 10 on the bottom plate 7 extending along one edge of the opening 8 whereby depression of the slidable member will sever a stamp from the roll of stamps (not shown) as the knives come in contact with each other.

The roll of stamps may be mounted within the housing and slidable member, and for this purpose a bolt 11 is provided transversely from side to side of the housing extending through suitable vertical slots 12 in the slidable member so as not to interfere with movement of said slidable member and at the same time provide a support fixed with respect to the housing for the stamps. It is to be understood that this bolt 11 may be removed so as to enable the same to be inserted through the center of the roll of stamps. A guide plate 13 extends from substantially opposite the bolt 11 downwardly toward the bottom plate 7 so as to bring the stamps as they are unwound to a position registering with the opening in the bottom plate. This guide plate may be made in any suitable manner and by way of illustration I have shown the same provided with flanges 14 which will receive the edges of the strip of stamps coming from the roll and retain the same next to the body portion of the guide plate. In order to insure easier movement of the stamps, a roll 15 is shown at the upper end of the guide plate.

In order to obtain an intermittent feeding of the strip of stamps from the roll I provide a pushing device in the nature of a pawl or ratchet which will feed the stamps

onward as the slidable member rises, thus placing a new stamp in position over the opening 8 immediately after the previous stamp has been affixed. In order to provide 5 such a pawl, I preferably pivot a first class lever 16 at one side of the housing and pivot a corresponding arm 17 at the opposite side of the housing, the lever and arm having pivots 18 and 19 respectively in alignment 10 with each other. The lever and arm 16 and 17 project in the same general direction beyond the edge of the housing and are connected at their outer ends by means of a cross rod 20. The lever 16 is slotted as at 21 at 15 its inner end, the slot engaging over a pin 22 projecting through a vertical slot 23 in the housing. The pin 22 is connected to the slidable member 5 so that up and down movement of the slidable member will result 20 in a swinging movement of said lever 16. At about the middle of said cross rod is pivotally carried a pawl 24 which is actuated by a suitable spring 25 shown upon the rod 20 pressing the end of the pawl toward 25 the guide plate 13. It may be here observed that the radius of curvature of the guide plate has its center on the axis of pivoting of the arm and lever so that the pawl will follow around the guide plate when the arm and lever are swung upon their axis.

In order to hold the stamps so they will not be disturbed or retracted while the pawl is travelling upwardly on the guide plate, I provide a holding finger 26 which projects inwardly through a slot 27 in the housing at substantially the end of the guide plate 13 and operated from the outside of the housing by means of a bell-crank lever 28. Said bell-crank lever 28 is pivoted on 35 the same pivot 19 as arm 17 and provides an arm 29 having a slot 30 within which rides a pin 31 projecting outwardly through a slot 32 in the housing and secured to the slidable member 5. By this means it will 40 be observed the bell-crank lever 28 will be swung as the slidable member is depressed and such swinging of the bell crank lever operates to depress finger 26. A suitable spring 33 is arranged to hold the finger 26 45 in proper position when not operated upon by the cam.

In order to moisten the stamps immediately before application thereof, I provide a water container 34, preferably of glass, 55 which may have formed therewith or may be connected to a very fine outlet 35 on the bottom plate 7 adjacent opening 8 in such position as to direct the water ejected therefrom beneath the stamp before it is cut off 60 and pressed down. In the structure shown, the water container is provided with a rubber bulb 36 at its upper end, the bulb having a transverse yoke 37 extending across the same by which pressure may be exerted in 65 the container. The yoke is shown held with-

in a hook or bracket 38 at one end and in engagement with a slide bar 39 at its other end. The slide bar 39 extends downwardly on the outside of the housing and has an inwardly directed projection 40 at its lower end inserted through a slot 41 in the housing. This projection 40 underlies a cam 42 pivotally mounted on the inside of the housing adjacent the slidable member 5. A suitable finger 43 projects from the cam into an opening 44 in the slidable member, the parts being so arranged that vertical movement of the slidable member 5 will operate upon said finger 43 to swing the cam which in turn engages projection 40 on the slide bar. 70 In this manner, every time the slidable member is depressed the parts operate to squeeze bulb 36 and eject a drop of water through opening 35 beneath the stamp. For the purpose of admitting air into the container and bulb when the external pressure is relieved and the bulb resumes its normal shape, I have shown an inlet valve 45 which opens into said container immediately below the bulb. The valve will not admit air passing outwardly when the bulb is compressed, but will admit air entering when the bulb 80 expands.

Operating the slidable member downwardly is obtained by manually depressing 95 the handle 3, and in order to retract the slidable member or raise it again a suitable spring 46 is provided between said handle and the housing. This spring is preferably contained within the collar 2 and is also 100 protected by means of a telescopic ferrule 47 attached to the handle and sliding over said collar 2.

Obviously detail changes and modifications may be made in manufacturing my 105 improved stamp placing machine, and I do not wish to be understood as limiting myself except as set forth in the following claims when construed in the light of the prior art.

Having thus described my invention, I 110 claim:

1. A stamp placing machine comprising a housing, means for supporting a roll of stamps therein, pawl operated means for intermittently feeding said stamps, means for injecting water beneath the stamp to be affixed, means for pressing the stamp in place, and a holding finger for preventing retraction of the strip of stamps.

2. A stamp placing machine comprising a housing, means for supporting the roll of stamps therein, pawl operated means for intermittently feeding said stamps, means for injecting water beneath the stamp to be applied, means for pressing the stamp in place, a holding finger for preventing retraction of the strip of stamps, and cooperating knife blades for severing said stamps from the roll.

3. The combination as set forth in claim 130

- 2, one of said knife blades being fixed, and the other movable in a vertical plane and being simultaneously operated with said water injecting means.
- 5 4. A stamp placing machine comprising a housing, means for supporting a roll of stamps therein, pawl operated means for intermittently feeding said stamps, a bulb for injecting water beneath the stamp to be affixed, means for pressing the stamp in place,

a holding finger for preventing retraction of the strip of stamps, cooperating knife blades for severing the stamps from said roll, and valved means for admitting air to said bulb as the several parts of the machine 15 are retracted to their normal operative position.

In testimony whereof I affix my signature.

ALFRED E. McMILLAN.
